L. S. BOLD

WIRE STRETCHER

Filed Sept. 13, 1923

FIG. 1

FIG. 2

FIG. 3

L.S. Bold Inventor

By

William J. Jacobi

Attorney

UNITED STATES PATENT OFFICE.

LEOPOLD S. BOLD, OF LA FARGE, WISCONSIN.

WIRE STRETCHER.

Application filed September 13, 1923. Serial No. 662,469.

To all whom it may concern:

Be it known that LEOPOLD S. BOLD, a citizen of the United States, residing at La Farge, in the county of Vernon and State 5 of Wisconsin, has invented certain new and useful Improvements in Wire Stretchers, of which the following is a specification.

This invention relates to a wire stretcher and has for its principal object to provide 10 a device which is especially adapted for use in connection with the splicing of a broken fence wire.

Another important object of the invention is to provide a wire stretcher of the 15 above mentioned character, which is simple in construction, inexpensive, strong, durable and further well adapted for the purposes for which it is designated.

A further object of the invention is to 20 provide a wire stretcher of the above mentioned character, which may be easily and quickly adjusted in proper position with respect to the broken strands of wire in order to enable the same to be readily actuated for 25 causing the free ends of the wire to be stretched and spliced.

Other objects and advantages of this invention will become apparent during the course of the following description.

30 In the accompanying drawings forming a part of this specification and in which like numerals designate like parts throughout the same:—

Figure 1 is a view showing my improved 35 wire stretcher in use,

Figure 2 is a front elevation of the wire stretcher,

Figure 3 is a side elevation thereof,

Figure 4 is a section taken on line 4—4 40 of Figure 2;

Figure 5 is a section taken on line 5—5 of Figure 2, and

Figure 6 is a perspective view of the claw.

In the drawings wherein for the purpose 45 of illustration is shown the preferred embodiment of my invention, the numeral 1 designates the elongated lever which is provided with a centrally located aperture 2 and in which is adapted to be supported the

50 reduced neck portion 3 of the enlarged cup-shaped member designated generally by the numeral 4. The cup 4 and the neck portion 3 is provided with a centrally formed aperture 5. The cup-shaped member 4 has

55 its annular flange 6 provided with notches 7 on opposite sides of the center thereof ex-

tending inwardly from the outer edges thereof. These notches are indicated by the numeral 7 in the drawings and the purposes of which will be hereinafter more fully 60 described.

Adapted to extend through the central aperture 5 is the threaded bolt 8 and is provided with an enlarged head 9 which is adapted to be seated within the cup-shaped 65 member 4 in a manner as more clearly shown in Fig. 4 of the drawings and the purpose of which will also be hereinafter more fully described. The threaded end of the bolt 8 extends through the reduced portion 3 of the 70 cup-shaped member 4 and through the lever 1 and is adapted to receive the suitable washers 10 and the locking nut 11 whereby the head of the bolt 9 is held in proper position within the cup-shaped member 4. 75

Slidably mounted on the lever 1 is the substantially U-shaped member designated generally by the numeral 12 and this U-shaped member 12 has its arms 13 and 14 respectively extending beyond the side edge 80 of the lever 1 and are provided with registering apertures adjacent their outer ends thereof for the purpose of receiving the elongated reduced portion 15 of the cup member 16. The cup member 16 is substantially of the same construction as the cup member 4 heretofore described and is also adapted to be associated with a locking bolt 17 provided with an enlarged head 18 in a similar manner to the locking bolt 8 and as the construction 85 of the clamping means in connection with the U-shaped member 12 is of the same construction as that associated with the aperture 2 of the lever 1, it is not thought necessary to further go in detail as to the construction of the same it being sufficient to state that the wire clamping means associated with the sliding member 12 is identical with the wire clamping means which is held in a secured position within the aperture 2 of the lever 1.

In use, when it is desired to stretch the free ends of a strand of a broken fence wire in order to splice the ends, the lever is held in the position as shown in Fig. 1 of the drawings and one end of a strand of wire 19 is placed across the upper face of the cup-shaped member 4 so that the wire fits within the registering notches 7 and the bolt 8 is then inserted in the cup-shaped member in the manner as heretofore described so that the head portion 9 thereof will engage the 100

shaped member 4 and upon adjusting the lock nut 11 on the threaded end of the bolt 8 the headed portion 9 will be caused to draw the wire downwardly against the base of the 5 cup-shaped member 4 whereby the wire will be held in a securely clamped position between the head of the bolt 9 and the cup-shaped member 4 as more clearly shown in Fig. 4 of the drawings and the possibility 10 of the wire becoming disengaged from the wire clamping means will be avoided.

The other end of the broken wire is in a similar manner secured to the wire clamping means associated with the U-shaped member 12 and is also locked in a similar manner in the cup-shaped member 16. After the free ends of the wire have been securely 15 locked in proper position in the rigid clamping member 4 and the movable clamping member 20 member 12, the U-shaped member is then adjusted along the lever 1 to a point in close proximity to the wire clamping member 4. After the U-shaped member 12 has been moved to the proper position along the lever 25 1, the lever is then moved in the direction indicated by the arrows in Fig. 1 so that the crown portion of the U-shaped member 12 will frictionally engage the rear edge of the lever 1 and bind the same in position thereon 30 so as to prevent the accidental moving of the clamping means associated with the outer ends of the U-shaped member and enable the free ends of the wire to be stretched so as to enable the ends of the wire to be 35 brought together and spliced, in the well known manner. To further aid in joining the wires together any suitable ordinary clamping means may be used in conjunction with the wire stretcher.

40 In this manner the broken ends of a wire strand may be readily and quickly stretched and spliced and the action of the stretching element will at all times assure the proper stretching of the wire in order to accomplish 45 the necessary results. The simplicity in which the broken ends of the wire may be readily united furthermore enables the wire stretcher to be used in a manner which will save considerable time and labor and at the 50 same time assure the proper results.

When it is desired to stretch one end of a wire after the same has been used for a considerable length of time and has sagged, I 55 employ a device as more clearly shown in Fig. 3 of the drawings wherein the lever 1 is adapted to support the plate 20 which is secured thereto by a suitable bolt 21 passing through suitable apertures provided in the lever and plate. The plate 20 is provided 60 with an angular extension 22 which extends adjacent one of the side edges of the lever 1 and this angular extension 22 is split longitudinally as shown at 23 and the free end of the split extension is bent outwardly where- 65 by to provide substantially a V-shaped slot

into which may be inserted the strand of wire. This will enable the tool to be readily operated. This angular extension 22 may furthermore be termed a claw and in use, the strand of wire to be stretched is inserted 70 in the wedge-shaped slot 23 by having the free ends of the lever 1 engaging the fence post or other suitable object to which the strand of wire is fastened and a downward pull exerted on the lever will cause the wire to become stretched and the same may be held in such a position until stapled to the fence post in a well known manner. To furthermore enable the strand of wire to be held in position within the claw while the same is being stretched, the free end of the wire may be wrapped around bolts 21 which support the plate 20 on the lever 1 by loosening the lock nut 25.

75 It will thus be seen from the foregoing, 80 that a wire stretcher has been provided which may be used for a number of various purposes and will frictionally stretch the wire to the desired degree in order to enable the same to be readily operated upon.

85 From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion and in the minor details of construction may be resorted to, without departing 90 from the spirit or sacrificing any of the principles of the invention.

95 What I claim as new and desire to secure by Letters Patent is:

100 1. A wire stretcher of the class described comprising an elongated lever, a wire clamping member carried by said lever, said wire clamping member including a cup-shaped member having a central aperture therein, a bolt having its head seated in said cup-shaped member and its shank passing through said aperture, a lock nut therefor, 105 said cup-shaped member provided with notches in the annular flange thereof, to receive the free end of a wire, said bolt having 110 its head portion engaging the portion of the wire extending across said cup-shaped member to clamp the same thereon.

115 2. A wire stretcher of the class described comprising an elongated lever, a wire clamping member detachably secured thereon, a second wire clamping member slidably mounted on said lever, each wire clamping member including a cup-shaped member having an annular flange provided with notches arranged on opposite sides of the center of said cup-shaped member, said cup-shaped member having a central aperture 120 adapted to receive a threaded bolt, the head 125 of said bolt adapted to be seated in said cup- 130

shaped member and also engage the wire extending across the cup-shaped member in the notches thereof to clamp the wire in said cup-shaped member, and a locking nut carried on the threaded end of said bolt for locking the head of the bolt in engagement with the wire.

3. A wire stretcher of the class described comprising an elongated lever provided with 10 an aperture therein, a wire clamping member including a cup-shaped member and having a reduced neck portion receivable in said aperture, means for securing said cup-

shaped member on said lever, a second wire clamping member slidably mounted on said lever, the latter including a substantially U-shaped member having its arms embracing said lever and the outer ends thereof extending beyond the side edges of said lever, said U-shaped member provided with registering 15 apertures adjacent the outer ends thereof for receiving one clamping means, and means for securing the same therein.

In testimony whereof I affix my signature.

LEOPOLD S. BOLD.
